UNITED STATES PATENT OFFICE.

CARL FLOHR, OF BERLIN, AND REINHARD DIETZE, OF COSWIG, GERMANY.

RHEOSTAT.

SPECIFICATION forming part of Letters Patent No. 649,927, dated May 22, 1900.

Application filed July 3, 1899. Serial No. 722,712. (No model.)

To all whom it may concern:

Be it known that we, CARL FLOHR, of Berlin, and REINHARD DIETZE, of Coswig, Germany, have invented certain new and useful 5 Improvements in Rheostats; and we do hereby declare the following to be a full, clear, and exact description of the invention, such as will enable others skilled in the art to which it app pertains to make and use the same, reference 10 being had to the accompanying drawings, and to letters of reference marked thereon, which form a part of this specification.

The rheostats hitherto employed for high-potential currents and comprising a mass of 15 pulverulent resisting material, into which a regulating contact-piece is dipped to a greater or less depth, are attended by the disadvantage that when they are being operated the metallic powder sticks to the insulating portions of the 20 apparatus, whereby paths are made for the current that cause short circuits and disturbances of working. This disadvantage is ob viated according to the present invention by means of a special sliding contact device that 25 is connected with the regulating contact-piece and by means of which, for the sake of safety, the circuit is again broken after the regulating contact-piece has passed out of contact with the mass of resisting material; but that 30 our invention may be fully understood we will describe the same in detail, reference being had to the accompanying drawings, in which—

Figures 1 and 2 are vertical sections of a rheostat embodying our invention and showing 35 the contact-arm in different positions. Fig. 3 is a cross-sectional view thereof, the contact-arm B being removed from its spindle; and Fig. 4 is a left-hand elevation of Fig. 3.

40 In the drawings, A indicates a suitable closed box or receptacle made of a non-con ductive material and having bearings in two of its opposite sides at a suitable elevation for a spindle G, of conductive material, carrying 45 within the box a radial conductor or contact arm B and on the outside of said box a contact-arm c. In the path of the contact-arm B, within the receptacle, is arranged a contact-spring C, connected to a binding-post H, 50 to which is connected the negative pole of an electric circuit, and on the outer face of the box A is arranged a fixed conductor or con

tact in the form of a segmental plate a, con centric with the spindle G, and a small plate b, both in the path of contact-arm c, said con tact-plate a being connected by wire F to a binding-post E, to which is connected the positive pole of the electric circuit.

The box A is partly filled with a pulveru lent metallic resistance material m, and the 60 contact-arm B is so arranged on its spindle G that by suitably rotating the latter by means of the crank b' the said arm is caused to penetrate into said resistance material to a greater or less extent and to thereby vary 65 the degree of resistance to the passage of the current, while when said spindle is turned to move the arm out of the resistance material the contact-arm c will lie on plate b and the rheostat will be cut out of the circuit. When 70 the contact-arm B is in the position shown in Fig. 1, for instance, current flows from E via F to fixed contact a, trailing contact c, spindle G, resistance material m, contact-spring C, and negative binding-post H. If, on the 75 contrary, the spindle G is turned to bring the conductor-arm B in direct contact with spring C, Fig. 2, then current will flow as be fore to said contact-arm B and thence direct to spring C, thus forming a short circuit and 80 cutting the resistance out, as will be readily understood.

The relative radial position of the contact arm B and the trailing contact c on spindle G is such that when in their normal positions 85 the said trailing contact c lies in advance of contact-arm B in the direction in which the spindle G is to be turned to move the said arm B into the resistance material m to a greater or less extent, and the arrangement 90 of the contact-plate a is such that the trailing contact c will contact with said plate a before the contact B comes into contact with said resistance material, the reverse taking place in switching the rheostat out of the cir cuit. The arm B will move out of contact with the resistance material m before contact c breaks contact with a, thereby avoiding the difficulties above referred to.

Having thus described our invention, what 100 we claim as new therein, and desire to secure by Letters Patent, is—

1. A rheostat comprising two stationary contacts insulated from each other, one of

said contacts consisting of a resistance material, in combination with two movable contacts coöperating with said stationary contacts, and means for shifting said movable contacts so that one will contact with the resistance material after the other has made contact with its stationary contact, for the purpose set forth.

2. A rheostat comprising two stationary contacts insulated from each other, one of said contacts consisting of a resistance material, in combination with two movable contacts coöperating with said stationary contacts, and means for shifting said movable contacts so that one will contact with the resistance material after the other has made contact with its stationary contact, and so that in reversing the motion of said movable contacts they will break contact with their respective stationary contacts in reverse order, for the purpose set forth.

3. A rheostat comprising two stationary contacts insulated from each other, one of said contacts consisting of a comminuted resistance material, in combination with two movable contacts one of which is adapted to be moved to a greater or less extent into said resistance material, and means for shifting the movable contacts so that one will contact with or enter into the resistance material after the other has made contact with its stationary contact and so that in reversing the motion of the movable contacts they break contact with their respective stationary contacts in reverse order, for the purpose set forth.

4. A rheostat comprising two stationary contacts insulated from each other, one of said contacts consisting of a resistance material, in combination with two movable contacts coöperating with said fixed contacts,

means for shifting said movable contacts so that one will contact with the resistance material after the other has made contact with its fixed contact, and means for short-circuiting the movable contact which coöperates with the resistance material and cut the latter out of circuit, for the purpose set forth.

5. A rheostat comprising two stationary contacts insulated from each other, one of said contacts consisting of a comminuted resistance material, in combination with a movable contact coöperating with and adapted to penetrate to a greater or less extent into the resistance material, a movable contact coöperating with the other stationary contact, means for shifting said contacts so that one will contact or enter the resistance after the other makes contact with its stationary contact, and means for short-circuiting the movable contact that coöperates with the resistance while in contact therewith, for the purpose set forth.

6. A rheostat comprising a box, a comminuted resistance material partly filling the same, the spring C partly embedded in said material and the segmental contact-plate a and the contact b on the outside of the box, in combination with the conductive spindle G, the radial contacts B c thereon, and means for circuiting the aforesaid spring C and contact a, said parts arranged relatively to one another and operating substantially as and for the purpose specified.

In testimony that we claim the foregoing as our invention we have signed our names in presence of two subscribing witnesses.

CARL FLOHR.
REINHARD DIETZE.
